JOSEPH W. REESE, OF SALT LAKE CITY, UTAH.

CLAMPING DEVICE.

1,078,378.

Specification of Letters Patent. Patented Nov. 11, 1913.

Application filed April 24, 1913. Serial No. 763,308.

To all whom it may concern:

Be it known that I, JOSEPH W. REESE, a citizen of the United States, and a resident of Salt Lake City, in the county of Salt Lake and State of Utah, have invented a new and useful Improvement in Clamping Devices, of which the following is a specification.

My invention is an improvement in clamping devices, and has for its object to provide mechanism of the character specified, especially adapted for use with ties other than wooden ties, and wherein means is provided for holding the rail firmly to its seat on the tie, capable of being released when desired, and without the use of spikes and the like.

In the drawings:—Figure 1 is a top plan view of the improved clamping device in place, Fig. 2 is a side view of the clamping device, the rail and the tie being in section. Fig. 3 is a perspective view of one of the clamps, and Fig. 4 is a similar view of the rail seat.

The present embodiment of the invention is shown in connection with a tie of metal composed of a base or bottom 1, having transversely arranged teeth or corrugations for gripping the road bed to prevent longitudinal movement of the tie and having upstanding side walls or flanges 3. The tie is thus of channel shape, and the channel may be filled with concrete or the like plastic material capable of hardening to make the tie of sufficient weight. At the points where the rails cross the tie, each of the side walls or flanges 3 is extended upwardly and each of the said extensions is provided with a notch or recess 4, the said notch or recess 40 being of a width to receive the base 5 of the rail and of a depth approximately equal to that of the rail. The upper edges of the side walls of each notch 4 and at the junction of the edges of the extension with the side wall, the said side wall is provided with a notch or recess 9, each of the said notches or recesses inclining inwardly and downwardly as shown. It will be understood that the notches 4 of the opposite side walls 55 are in alinement at each end of the tie and

that the rail extends transversely of the tie, seating in the said registering notches.

A pair of clamping jaws is provided for each rail, each of the said jaws 10 being of a width sufficient to extend from one side 60 wall 3 to the opposite side wall and each of the said jaws is provided at its free edge with an enlargement 11, fitting between the base flange 5 and the tread 6 of the rail and engaging the web 12 of the rail to prevent 65 movement of the rail in any direction. The free edge of the said enlargement 11 is shaped to fit the web of the rail and the under face of the tread and the upper face of the adjacent side of the base flange. At 70 the opposite end of the jaw from the enlargement 11, each of the said jaws is provided with oppositely extending lugs or journal pins 13, the said journal pins being adapted to engage the notches 9, at the adjacent side of the rail. It will be understood that the notches 9 on each side of each rail are in register, and the clamping jaws 75 may be removed or inserted, by lifting the end of the said jaw remote from the enlargement 11, upwardly and outwardly, to cause the journal pins 13 to disengage from the slots 9.

Each of the clamping jaws is provided with an integral extension 14, at the end adjacent to the journal pin, each of the said extensions extending inwardly approximately parallel with the body of the jaw and in downwardly spaced relation and the upper face of each of the said extensions is 80 provided with a plurality of recesses 15, as indicated in Fig. 3.

A rail seat is also provided for each rail, one of the said seats being shown in Fig. 4. Each of the said rail seats 16 is of a width 85 to fit between the side walls 3 of the tie and each seat is provided on its upper face at the center thereof with a plane surface 17, upon which the base flange 5 of the rail rests, the said plane surface being of a width 90 corresponding to the width of the base flange. From the plane surface 17 the upper face of each seat inclines downwardly toward the ends of the seat as indicated at 18, and at each end the upper face of the seat is rounded as shown at 19 to fit between the extension 14 and the body 10 of the adjacent gripping jaw. The portions 18 and 19 of the seat are shaped to fit the under faces of the gripping jaws 10 smoothly and 100

110

closely, and that portion of the under face of the seat adjacent to the ends thereof is shaped to roughly fit the upper face of the extension 14 as indicated at 20. The seat 5 is arranged as shown in Fig. 2, the ends thereof being received between the gripping jaws and the extensions, and at each of the portions 20 the seat is provided with depending lugs 21, the said lugs being shaped 10 to fit the recesses 15 and being received in the said recesses. When the seat and the jaws are in place, there is just sufficient room between the face 17 of the seat and the under faces of the inner ends of the gripping jaws 15 to receive the base flange of the rail, and the said flange is held between the inner ends of the jaws and the upper face of the seat.

Each extension of each side wall is provided with an opening on each side of each 20 notch, each opening being at the rounded portion 7, and the openings at each side of each rail register to receive a locking pin 22. Each of the said locking pins extends transversely of the tie, above the inner end of the 25 adjacent gripping jaw, to prevent upward movement of the said jaw, thus locking the inner end of the jaw to the tie.

The seat 16 is a bridge extending between the extensions 14 of the gripping jaws and seated 30 on the said extensions. The said bridge or seat not only supports the rail at this point but also absolutely prevents upward movement of the inner ends of the gripping jaws, acting thus as a locking member in addition to its function as a 35 bridge and rail seat.

It will be noticed from an inspection of Fig. 2 that the rail does not touch the tie, the under face of the base flange being spaced 40 above the bottom walls of the notches 4.

The principal objection to ties of metal and concrete is the lack of resiliency of the said ties, and attempts have been made to overcome this disadvantage by inserting 45 wooden blocks, springs or the like. With the present construction however, the rail is supported on a yielding seat. It will be noted that between the surfaces 20 on the under face of the seat, the said seat is recessed or cut away transversely and the seat 50 is supported at its ends, being free intermediate the ends. Thus a considerable degree of resiliency is imparted to the seat. Furthermore since the seat is supported on the 55 extensions, and the jaws may rock slightly, a considerable degree of resiliency is obtained, sufficient to dispense with cushions or springs.

When the locking pins 22 are removed, 60 either jaw may be removed, while when in place, the said pins prevent accidental displacement of the jaws while at the same time not interfering with the resiliency of the seat. The lugs 21 by their engagement

with the recesses 15, provide a lock to prevent displacement of the jaws outward, thus effectually providing against accidental displacement of the seat. It will be evident also that the greater the weight of the rail the more tightly will the rail be gripped 70 by the jaws.

The improved clamping device will effectually hold the rail to the seat without the necessity of wedges, spikes, bolts or the like, and at the same time the said jaws permit 75 access to the different elements, for repairs or the like.

I claim:—

1. In combination with the rails, a tie of channel shape having its side walls extended 80 upwardly at the points where the rails cross the tie, each of the said extensions having a notch for receiving the rail and having an opening at each side of the notch near the top thereof and having a recess at each 85 side of the extension, each of the said recesses inclining inwardly and downwardly, a rail seat arranged between the side walls of the tie, said seat having its upper face flattened at the center thereof to form a 90 seat for the rail base flange, said seat being arched longitudinally and having at each end on its under face a plurality of depending lugs, a pair of gripping jaws, each of the 95 said jaws having oppositely extending journal pins at its outer end for engaging the recesses at one side of the rail, the inner end of each jaw being shaped to fit the upper face of the base flange, the web, and the under face of the tread of the rail, each of 100 the said jaws having at its outer end an inward extension fitting beneath the adjacent end of the rail seat, each extension having openings in its upper face for receiving the lugs of the seat, and locking pins engaging 105 the openings at each side of the notch above the inner ends of the clamping jaws.

2. In combination with the rails, a tie of channel shape having oppositely arranged pairs of notches in its side walls near the 110 ends thereof for receiving the rails, a rail seat arranged between the side walls of the tie at each end thereof for receiving the rail, said seat being arched longitudinally and having depending lugs at each end 115 thereof and a pair of gripping jaws for the rail at each seat, each of the said jaws engaging the web and base of the rail at its inner end and having an inward extension at its outer end upon which the adjacent 120 end of the rail seat rests, each extension having recesses for receiving the lugs of the seat, each of the said gripping jaws having oppositely extending journal pins at the junction of the extension therewith and the 125 side walls of the tie having notches for receiving the journal pins, said notches inclining inwardly toward the rail at their

lower ends, the side walls of the tie having registering openings at each side of each rail above the adjacent gripping jaw, and a pin engaging each pair of openings for holding the jaw in place.

3. In combination with the rails, a tie of channel shape having oppositely arranged pairs of notches in its side walls near the ends thereof for receiving the rail, a rail seat arranged between the side walls of the tie at each end thereof for receiving the rail, said seat being arched longitudinally and having depending lugs at each end thereof and a pair of gripping jaws for the rail at each seat, each of the said jaws engaging the rail at its inner end and having an inward extension at its outer end upon which the adjacent end of the rail seat rests, each extension having recesses for receiving the lugs of the seat, each of the said gripping jaws having oppositely extending journal pins at the junction of the extension therewith, and the side walls of the tie having notches for receiving the journal pins, said notches inclining inwardly toward the rail at their lower ends, and means adjacent to the rail for preventing upward movement of the jaws.

4. In combination with the rails, a tie of channel shape having oppositely arranged pairs of notches in its side walls near the ends thereof for receiving the rails, a rail seat arranged between the side walls of the tie at each end thereof for receiving the rail, said seat being arched longitudinally and having depending lugs at each end thereof and a pair of gripping jaws for the rail at each seat, each of the said jaws engaging the rail at its inner end and having an inward extension at its outer end upon which the adjacent end of the rail seat rests, each extension having recesses for receiving the lugs of the seat, each of the said jaws having a detachable pivotal engagement with the tie near the junction of the extension with the jaw, and releasable means engaging each jaw adjacent to the rail for preventing upward movement of the jaw.

5. In combination with the rails, a tie of channel shape having oppositely arranged pairs of notches in its side walls near the ends thereof for receiving the rail, a rail seat arranged between the side walls of the tie at each end thereof for receiving the rail, a gripping jaw at each side of each rail for engaging the web and base of the rail, each jaw having a detachable pivotal connection with the tie at its outer end and having an extension at the said outer end upon which the adjacent end of the rail seat rests, and releasable means engaging the inner end

of each jaw to prevent upward movement thereof.

6. In combination with the rails, a tie of channel shape, a seat for each rail arranged between the side walls of the tie, a gripping jaw having a detachable pivotal connection with the tie at each side of each rail, each jaw engaging the web and base of the rail, and each jaw having an extension at its outer end upon which the adjacent end of the seat rests, each extension having recesses in its outer face and the seat having lugs for engaging the recesses.

7. In combination with the rails, a tie of channel shape, a seat for each rail arranged between the side walls of the tie, a gripping jaw having a detachable pivotal connection with the tie at each side of each rail, each jaw engaging the web and base of the rail, and each jaw having an extension at its outer end upon which the adjacent end of the seat rests, and means in connection with the extensions and the seat for preventing movement of the extensions away from the seat.

8. In combination with the rails and the ties for supporting the rails, a seat at each end of each tie upon which the rails rest, a gripping jaw pivotally connected to the tie on each side of each rail and engaging the rail above the seat, each jaw having an inward extension upon which the adjacent end of the seat rests, and means in connection with the seat and the extensions for preventing movement of the extensions away from the seat.

9. In combination with the rails and the ties for supporting the rails, of a seat for each rail, a gripping jaw having a detachable pivotal connection with the tie at each side of the rail, each jaw engaging the rail above the seat to clamp the rail to the seat, and each jaw having an extension at its outer end upon which the seat rests, and releasable means adjacent to the rail for preventing upward movement of the clamping jaws.

10. In combination with the rails, and the ties for supporting the rails, a seat for each rail, a gripping jaw at each side of each rail, each jaw engaging the rail for holding it to its seat and having an extension upon which the adjacent end of the seat rests, each jaw being pivoted to the tie, and means in connection with the seat and the jaws for preventing disengagement of the seat and the jaws.
